UNITED STATES PATENT OFFICE.

FRANKLIN F. KNOUS, OF HARTFORD, CONNECTICUT, ASSIGNOR TO THE COLTS
PATENT FIRE ARMS MANUFACTURING COMPANY, OF SAME PLACE.

MAGAZINE FIRE-ARM.

SPECIFICATION forming part of Letters Patent No. 324,330, dated August 11, 1885.

Application filed June 15, 1885. (No model.)

To all whom it may concern:

Be it known that I, FRANKLIN F. KNOUS, of Hartford, in the county of Hartford and State of Connecticut, have invented new Improvements in Magazine Fire-Arms; and I do hereby declare the following, when taken in connection with accompanying drawings, and the letters of reference marked thereon, to be a full, clear, and exact description of the same, and which said drawings constitute part of this specification, and represent, in—

Figure 1, a sectional side view of so much of the arm as necessary to illustrate the invention; Fig. 2, a detached view of the dog, hammer, trigger, and rear portion of the slide, showing the hammer in the cocked and the dog in the locking position; Fig. 3, a top view of the parts seen in Fig. 1, the breech-piece removed to show the dog below; Fig. 4, a modification showing the adaptation of the trigger to operate the dog.

This invention relates to an improvement in that class of magazine fire-arms in which the breech-piece is arranged to move back and forth in a longitudinal line in rear of the barrel to open and close the breech, and in which the breech-piece is so moved by means of a handle arranged forward of the breech-piece, with an arm extending therefrom rearward to engage the breech-piece, so that in the rear movement of the handle the breech-piece is thrown to the rear to open the breech, and in the forward movement the breech-piece will be moved forward to close the breech, with special reference to the arm for which Letters Patent of the United States No. 285,020 were granted to W. H. Elliott, September 18, 1883.

In an arm of the character mentioned—such as the Elliott arm—when the hammer is in its closed position against the breech-piece, the mainspring of the arm is sufficient, acting through the hammer, to hold the breech-piece and its connected mechanism in the closed position; but if the hammer be thrown back toward its cocked position, then, the power of the spring being removed from the breech-piece, a sudden shock from the rear—say, as by dropping the arm upon its butt—will tend to throw the handle rearward, and thereby so

disengage the breech-locking mechanism that the breech-piece itself may move to the rear, and thereby allow the cartridge in the chamber of the magazine, as well as that which then rests upon the carrier, to drop from the arm 55 and be lost, thereby putting the arm out of condition for instant use, and requiring two movements forward and back of the breech-piece in order to transfer a new cartridge from the magazine to the barrel ready for firing.

The object of my invention is to avoid this accidental displacement of the cartridge; and it consists in a locking-dog, hung in the receiver, adapted to engage the operative mechanism of the arm when the breech-piece is in its closed position, combined with a moving part of the lock mechanism, whereby when the hammer is thrown forward into its firing position the said dog will be disengaged from its locked 70 position, leaving the handle and breech-piece free for rear movement, but when the hammer is thrown rearward toward its cocked position the dog will be left free to fly into engagement and hold the breech-piece in its closed 75 position, and as more fully hereinafter described.

In illustrating my invention I show only so much of the arm as is necessary for the understanding of the invention.

A represents the bottom portion of the receiver, which, extending to the rear, forms the trigger-guard B and the rear tang, C; D, the hammer, hung upon a pivot, a, in the usual manner and provided with the mainspring E; F, the trigger, hung upon a pivot, b, in the usual manner and adapted to engage the respective notches of the hammer; G, the handle, arranged to slide longitudinally on the carrier rearward to open the breech-piece and forward to close it, as in the Elliott arm. From the handle a slide, H, extends rearward through a forward extension, I, from the receiver, which extension serves as a guide for the slide H in its rear movement. The slide 95 is engaged with the locking mechanism of the breech-piece and the breech-piece itself, so that in its rear movement the breech-piece will be thrown rearward to open the breech, and in the forward movement the breech-piece 100

will be closed. The carrier is also actuated to transfer the cartridge from the magazine to the carrier in the usual manner. The actions between the breech-piece and the slide H and the breech-piece and the carrier, with its operative mechanism, are immaterial to this invention, it only being necessary that there shall be such connection between the breech-piece and the slide H that the longitudinal movement of the handle in one direction will open the breech-piece and on the return of the handle will close the breech-piece. I however show the brace and a portion of the breech-piece in the closed position in Fig. 1. When the handle is in its extreme forward position, the parts stand as seen in Fig. 1. The hammer, free, abuts against the rear end of the breech-piece, as shown.

In rear of the rear end of the slide H is a two-armed lever, *d e*, hung upon a pivot, *f*, forming the locking-dog, the forward arm, *d*, extending toward the rear end of the slide H and so that its nose stands in line with the said rear end, but below, as seen in Fig. 1, so as not to interfere with the rear movement of the slide. The other arm, *e*, of the dog extends rearward, and is turned up, as at *g*, forward of the hub of the hammer, and on the hub of the hammer is a cam or bearing surface, *h*, which, when the hammer is in its closed position, stands against the turned-up end *e* of the dog and holds that end up and the other arm, *d*, down out of the path of the slide H; but so soon as the hammer has been turned to the rear to a sufficient extent to take the bearing surface *h* from the dog, then a spring, *l*, is free to throw the nose of the dog up in rear of the slide H, as seen in Fig. 2, and so that it then forms a positive stop to prevent the rear movement of the slide, and the breech-piece, together with the slide, will be held in that closed condition until the hammer be thrown forward, in which forward movement the cam-surface *h* will strike the turned-up end *e* and throw the arm *d* downward, as seen in Fig. 1, to leave the slide and breech-piece free, and in this closed condition of the hammer and parts the slide is always free for rear movement. With the hammer in the closed position the movement of the handle rearward to throw the hammer to full-cock first carries the slide H over the nose of the dog, so that it will be prevented from rising. The rear movement of the breech-piece imparts the rear movement to the hammer, as in the Elliott arm, the dog having no effect in such rear movement. The hammer being left at full-cock and the handle moved forward to close the breech-piece, the dog will be free from the hammer, and so that as the breech-piece reaches its closed position and the handle its extreme forward position, the dog will fly up into its locked position, as seen in Fig. 2, and there support the parts independent of the hammer. The discharge of the hammer will disengage the dog and leave the parts free, as before described.

While I prefer to make the hammer directly the active agent to throw the nose of the dog from its locked position, it may be so moved by connection with either of the moving parts of the lock—as, for illustration, it may be as seen in Fig. 4. The cam or bearing surface may be upon the trigger, so that when the trigger is pulled, as in firing, it will pass beneath the rear arm of the dog, and there remain when the hammer is in its closed position; but as the trigger falls into either of the notches of the hammer the cam-surface of the trigger escapes the rear end of the rear arm of the dog and leaves it free, as before described, and so that in either case whenever the hammer is thrown to the rear to either of its notches upon the trigger the dog will be free to engage the slide.

By this construction the engagement and disengagement of the dog is made automatic, and without any care or attention on the part of the person using the arm, he being certain that whenever the breech-piece is in its closed position and the hammer turned therefrom, the breech-piece, with all its connecting mechanism, is locked against possible rear movement.

The modification which I have suggested to make the operation of the dog by the trigger will be sufficient to enable those skilled in the art to which this invention pertains to adapt any of the moving parts or points of the lock to so operate the dog.

I have represented the dog as engaging directly with the rear end of the slide; but it will be evident that it may engage at any other point on the slide, or, say, with the arm which extends down from the locking-dog through the slide, as indicated in broken lines, Fig. 2. By the term "slide," therefore, I wish to be understood as embracing such engagement of the dog therewith, directly or indirectly as will hold the slide in the manner described.

I claim—

1. In a magazine fire-arm in which the mechanism of the arm is operated by a handle arranged to move longitudinally beneath the barrel through a slide extending from said handle into connection with the breech mechanism, the combination therewith of a locking-dog hung in the receiver, one arm of which is adapted to engage said slide when the breech-piece is in its closed position, the other arm extending toward the lock mechanism, and a cam on said lock mechanism, substantially as described, and whereby when the hammer is in its closed position the said dog is thrown out of engagement with the breech mechanism, but is thrown into engagement by the rear or opening movement of the hammer.

2. In a magazine fire-arm in which the mechanism of the arm is operated by a handle arranged to move longitudinally beneath the barrel, with a slide extending from said handle into connection with the breech mech-

anism, the combination therewith of the two-armed dog *d e*, hung in the receiver in rear of said slide, the one of said arms, *d*, adapted to engage the said slide when the breech-piece 5 is in its closed position, the other arm extending rearward, the hammer constructed with a cam, *h*, adapted to operate upon said rear arm of the dog substantially as described, and whereby when the breech-piece is closed to and the hammer in its closed position the said

cam will force and hold the said dog from engagement with the said slide, but on the opening movement of the hammer the said cam will release the said dog to permit it to engage said slide, substantially as specified.

FRANKLIN F. KNOUS.
